UNITED STATES PATENT OFFICE

164,563

SOFA BED

Harry B. Fouts, Des Moines, Iowa, assignor to Sealy, Incorporated, Chicago, Ill., a corporation of Delaware

Application September 20, 1950, Serial No. 12,272

Term of patent 7 years

(Cl. D5—4)

To all whom it may concern:

Be it known that I, Harry B. Fouts, a citizen of the United States, residing at Des Moines, in the county of Polk and State of Iowa, have invented a new, original, and ornamental Design for a Sofa Bed, of which the following is a specification, reference being had to the accompanying drawings, forming a part thereof.

In the drawings:

I claim:

The ornamental design for a sofa bed, as shown.

HARRY B. FOUTS.
